UNITED STATES PATENT OFFICE.

CLARK J. BROWN, OF PETERSBURG, VIRGINIA.

NOTE-BOOK AND HOLDER FOR SAME.

1,152,702.

Specification of Letters Patent.

Patented Sept. 7, 1915.

Application filed July 19, 1912. Serial No. 710,413.

To all whom it may concern:

Be it known that I, CLARK J. BROWN, a citizen of the United States, and a resident of Petersburg, in the county of Dinwiddie and State of Virginia, have invented certain new and useful Improvements in Note-Books and Holders for the Same, of which the following is a specification, reference being had to the accompanying drawings.

10 This invention has relation to certain new and useful improvements in notebooks and holders for the same, and comprises two stiff board covers which are loosely connected by means of two similar spring wire holders 15 which permit the book covers to be folded back A-shaped, so that the book will stand upright: and the primary object of my invention, is to provide a notebook of a simple and inexpensive nature and of a compact 20 and durable construction, arranged so that new leaves can be easily inserted.

With these and other objects in view, the present invention consists in the combination and arrangement of parts as will be 25 hereinafter more fully described and finally pointed out in the appended claims, it being further understood that changes in the specific structure shown and described may be made within the scope of the claims, not 30 departing from the spirit of the invention.

In the accompanying drawings forming a part of this specification and in which like numerals of reference indicate similar parts in the several views: Figure 1, shows an edge 35 view of a notebook and holder constructed according to my invention. Fig. 2, shows an enlarged detached detail of one of the holders. Fig. 3, shows a sectional view 40 through the notebook, which is shown as closed. Fig. 4, shows the method of holding the book while in use. Fig. 5, shows an inner face view of the back cover with parts removed.

In my present invention I provide a notebook which is so constructed that the book can be folded back and held A-shaped, enabling the notes being easily read.

In carrying out the aim of my invention, I provide a stiff back cover 1, having two 50 apertures 2 near one edge, as indicated in Fig. 5, which are reinforced by means of the eyelets 3. Held below one of the flanges of each eyelet, in the manner shown in Figs. 3 and 5, is a terminal eye 4, forming part 55 of a spring wire holder, two such holders being used in my invention. Extending

from the terminal eye 4, is a base stem 5, having an offset shoulder 6, intermediate of its ends, the stem being continued at right-angles in an end section 7, from which extends an L-shaped hook 8, ending in the point 9 normally held within the connected securing eyelet, as is shown in Fig. 3. It will be noticed that the member 7, and the end 10 of the hook extend in parallel spaced 65 relation. These holders are made of spring wire.

Loosely held upon the hook extension, is a stiff top cover 12, while held between the covers 1 and 12, are the loose leaves 13. As 70 shown in Fig. 4, the covers 1 and 12 may be held in divergent spaced relation so that the book may stand on the ends of the covers with its leaves in an almost upright position, enabling the notes being easily seen. 75

In order to prevent the backs slipping outward, as might be the case upon a polished desk surface, I use a holder. In Fig. 1, I have shown a holder comprising the stiff cardboard members 14 and 21, which are 80 held V-shaped by means of a holder comprising a sheet metal member 15, having its ends 16, recurved to form suitable pin sleeves, engaging the shoulders 17, of a suitable clip. Each clip includes a loop 18, 85 while extending from the shoulders 17, are the stems 19, ending in the curved ears 20. The book covers 1 and 12, or the holder members 14 and 21, are arranged to be clamped between the loops 18 and the stem 90 19. These stems are held in spring pressed condition. The holder comprising the members 14 and 21, shown in Fig. 1, are intended to be used where notebooks are employed, having pliable covers. Where stiff covers 95 are used, these holding members are not necessary, and the spring clips are then secured to the lower edges of the stiff book covers in the manner shown in Fig. 4. While I have described the connecting member 15, as being made of sheet metal, the same can be made of pliable material, such as a tape. 100

A notebook constructed according to my invention, will lie perfectly flat on a desk or 105 table. Owing to the fact that the leaf holders are made of spring wire, the leaves can be easily removed and new ones substituted. The stiff covers further serve as a support for the tablet while transcribing notes. Further the front cover can be snugly folded 110 back against the back cover for convenience

in holding the notebook in the hand where that is necessary to take notes while standing.

A notebook constructed according to my invention is simple and inexpensive, and both durable and efficient.

Having thus described my said invention, what I claim as new and desire to secure by United States Letters Patent is:

10. 1. In combination, a stiff back cover having two apertures near one end, and two counterpart spring wire holders each including a terminal eye engaged by one of said apertures, a base stem continued from each eyelet, said stem having an off-set shoulder, intermediate of its ends, the holder being continued at right-angles in an end section from which extends an L-shaped hook ending in a point, normally held in the eyelet.
20. 2. In combination, a stiff back cover having two apertures near one end, an eyelet within each of said apertures, two counterpart spring wire holders each including a terminal eye engaged by one of said eyelets, a base stem continued from each eyelet, said stem having an off-set shoulder intermediate of its ends, the holder being continued at right-angles in an end section from which extends an L-shaped hook ending in a point normally held in the eyelet and a stiff front cover slidably held upon said hooks and at times upon said off-set base stem, as and in the manner set forth.
30. 3. In combination, a stiff back cover having two apertures near one end, two counterpart spring wire holders each including a terminal eye engaged by one of said apertures, a base stem continued from each aperture having an off-set shoulder intermediate of its ends, the holder being continued at right-angles in an end section from which

extends an L-shaped hook ending in a point normally held in the eyelet, a stiff front cover slidably held upon said hooks and at times upon said base stem, and a plurality of 45 leaves held upon said hooks.

4. In combination, a stiff back cover having two apertures near one end, an eyelet within each of said apertures and two counterpart spring wire holders each including a 50 terminal eye engaged by one of said eyelets, a base stem continued from each eyelet from which is continued at right-angles an end section from which extends an L-shaped hook ending in a point normally held in the 55 eyelet.

5. In combination, a stiff back cover having two apertures near one end, an eyelet within each of said apertures, two counterpart spring wire holders each including a 60 terminal eye engaged by one of said eyelets, a base stem continued from each eyelet from which is continued at right-angles an end section from which extends an L-shaped hook ending in a point normally held within 65 the eyelet, and means to connect said covers to their outer ends.

6. In combination, a stiff back cover having two apertures near one end, two counterpart spring wire holders each including a 70 terminal eye secured to said back in alignment with said apertures, a base stem continued from each eyelet from which is continued at right angles an end section from which extends an L-shaped hook ending in a 75 point as and for the purpose set forth.

In testimony whereof I affix my signature, in presence of two witnesses.

CLARK J. BROWN.
